ROPE MAKING MACHINE

Anton Kraft, Olpe, Germany

Application December 21, 1934, Serial No. 758,598
In Germany November 1, 1934

4 Claims. (Cl. 117—16)

This invention relates to a high-speed rope making machine, comprising a winding frame locked in position of rest in the rotary flyer and with a mechanism for pulling and winding the rope, in which the material provided with a preliminary twist is closed by the closing die before entering the machine by two rope lays continually neutralizing each other during each rotation of the flyer, whereas the rope is pulled forward along this flyer and fed in opposite direction to the winding drum into the winding frame over a pulley rotatably mounted on the flyer and changing the direction of the rope.

In the hitherto used machines of this type the pulley for changing direction of rope has a groove designed to enable a free untwisting of the rope material when passing over this pulley, said groove consisting of two mutually displaced rollers. If the material to be twisted is of thin metal wire or fibrous material, as is frequently employed for the production of small healds, it happens, that the thin heald, when passing over the pulley, cannot turn the rollers, with the result that the backward turning of the material takes place not at all or only partly, whereby undesirable, prejudicial tensions and distortions are imparted to the material during the twisting.

This inconvenience is overcome by the invention in that an arrangement is made, by which the roping material when passing over the pulley for changing direction of rope is positively turned backwards, so that the rope is uniformly twisted. The invention therefore represents an important improvement in the art of rope making.

The rope rolls in oblique direction to the plane of rotation of the pulley for changing direction of rope so that it must carry out one back twist in the sense of the direction in which the flyer turns while running over a portion of the pulley corresponding to two lay lengths. The pulley for changing direction of rope has a rolling surface which is domed from the middle towards both sides in order to conduct the rope over the pulley, in left-side or right-side oblique position according to the direction of the rotation of the flyer. The angle of obliquity determined by the thickness of the rope and the number of back turnings necessary for one half rotation of the pulley is adjusted by a nozzle which guides the rope and which is shiftably mounted on the flyer disc closest to the pulley.

An embodiment of the invention is illustrated by way of example in the accompanying drawing, in which:—

55 Fig. 1 shows the machine in front elevation.

Fig. 2 shows a constructional detail in medial longitudinal section.

Fig. 3 is a cross section on line III—III of Fig. 1, partly in elevation.

Fig. 4 shows the rope reversing pulley viewed 5 from the bearing bracket on the right of Fig. 1.

The flyer consisting of the discs 3, 4, 5 and 6 and of the connecting rods 7, rotates in the bearing brackets 1 and 2, the winding frame 8 for the drawing mechanism 9 and the winding drum 10 being locked in its position of rest in this flyer. A belt pulley 11 is mounted on one side of the machine and a closing die 12 on the other side, the laying plate 13 feeding the several wires to the closing die being arranged outside the machine proper. The rope 14, after being closed with a suitable preliminary twist in the closing die 12, is conducted through the hollow shaft 15 in the bracket 1 and thence over the pulley 16 mounted on the flyer-disc 4, along the flyer parallel to the axis of rotation thereof and its direction of travel is reversed when running over a pulley 17 between the flyer discs 5 and 6, whereupon the rope is drawn into the winding frame 8 where it is finally wound on the drum 18 over 25 the heald arrangement 19.

A spur wheel 20, fixed on the flyer-disc 3, meshes with a transmission wheel 21 of similar diameter keyed on the shaft, of a spur wheel 23 which drives the hollow shaft rigidly connected 30 with the closing die 12. The ratio of transmission of the wheels 20, 21, 22 and 24 is such that the closing die 12, during one rotation of the flyer, rotates twice in the same direction as the flyer, thus producing two rope twists. 35

The pulley 17 for changing direction of rope is rotatably mounted in the arms 25 which connect the flyer-discs 5 and 6. On the opposite side of the axis of rotation of the flyer counter-weights 27 are mounted on rods 26, and also connect the 40 flyer-discs 5 and 6. The counter-weights 27 are of such dimensions and mounted in such a manner, that they counterbalance the turning moment of the pulley 17 for changing direction of rope and of the arms 25 and rope guiding elements. The perfectly balanced flyer can therefore rotate at uniform speed and free from vibration. 45

The surface of the pulley 17 for changing direction of rope is domed towards both sides 50 from the middle, i. e. from the running off side of the rope forming the extension of the axis of rotation of the flyer, so that it appears to be composed of two juxtaposed discs which are each one deeper at the middle and ascending as con- 55

convex surfaces towards the sides. Such configuration of the pulley 17 has in practice proved to be very practical. The radius of curvature R corresponds preferably to approximately the 5 diameter of the useful surface of the pulley. Whereas the rope runs off of the middle of the pulley 17 into the winding frame by the preliminary drawing it runs on to this pulley at one side thereof. For adjusting the oblique position of the rope 14 whilst running over the pulley 17 a slot 29 parallel to the axis of the pulley 17 is provided in the flyer-disc 5 at the height of the rope passing through the same, a nozzle 28 for guiding the rope being shiftably mounted on 10 this slot. The angle of the obliquity is determined by the thickness of the rope 14 on the one hand and by the number of backward twists necessary during one half rotation of the pulley 17.

20 The two twists imparted to the rope 14 laid in the closing jaw at every rotation of the rotary body are continually neutralized by two similarly directed back twists transmitted to the laying point. The one distortion of the rope takes 25 place when it comes out of the hollow shaft 15 at point 30, and is freely transmitted as a back twist directly to the laying point, so that it is only necessary to neutralize the distortion which takes place as the rope enters the winding frame 30 8 at the point 31. In order to attain this, the rope 14 conducted along the flyer must turn once about its axis in the same direction as the rotation of the flyer at every rotation of the rotary body. Consequently the rope, in running 35 off over the reversing pulley must twist in the direction in which the flyer rotates as many times as the number of lay lengths on the path of travel. These turnings are then freely transmitted as twists up to the laying point. The 40 similarly directed distortion of the rope corresponding to one rotation of the flyer is obtained, while the rope is running over the pulley 17 by the oblique direction of the rope, the nozzle 28 being shifted to the one half of the pulley 45 or to the other half of the same according to the direction of rotation of the flyer.

If the flyer rotates for example in the clockwise direction, viewed from the bearing block 2, and if the portion of the rope on the pulley 17 50 has eight turn lengths, the rope, in running over from the pulley, must carry out four twists in clockwise direction, viewed from the bearing block 2 (Fig. 4).

If, however, the flyer rotates in opposite direction, the running rope running on to the pulley 17 must be brought into the oblique position, indicated in dashlines by means of the nozzle 28. The nozzle 28 shown by way of example consists of a hollow, detachably fixed screw.

60 I claim:—

1. A high speed rope making machine, comprising in combination a machine frame, a flyer journalled in said frame and consisting of four discs connected by rods, a winding frame locked in position of rest within said flyer, a closing die on the outer side of said machine frame on the feed end of the machine and adapted to lay the rope prior to its entrance into the machine, a guide pulley on the second disc from the feed end of the machine adapted to guide the rope laid by said closing die, a reversing pulley carried by the third and fourth flyer discs and adapted to change the direction of travel of the rope and feed the same to said winding frame, and means for guiding the rope over said reversing pulley obliquely to the plane of rotation of said pulley, said pulley having an annularly grooved face defining annularly bulged portions adapted to cause the rope to roll laterally thereon to impart a back twist in the direction of rotation of the flyer while a length of rope equal to two rope lays is running over the pulley.

2. A high speed roping machine, comprising in combination a machine frame, a flyer journalled in said frame and composed of four discs connected by rods, a winding drum locked in position of rest with said flyer, a closing die on the outer side of said machine frame on the feed end of the machine and adapted to lay the 10 rope prior to its entrance into the machine, a guide pulley on the second disc from the feed end of the machine adapted to guide the rope laid by said closing die, a reversing pulley carried by the third and fourth discs and adapted 15 to guide the rope obliquely to the direction of rotation of the pulley to change the direction of travel of the rope and feed same to said winding frame, the face of said reversing pulley being domed from the middle towards both sides, 20 to cause the rope to roll thereon in the direction of rotation of said flyer, the third flyer disc from the feed end of the machine having a slot serving as passage for the rope, a nozzle shiftably mounted in the slot in said third flyer disc arranged parallel to the axis of rotation of said reversing pulley and adapted to conduct said rope to alter the angle of obliquity of the rope 25 on said pulley.

3. A high speed rope making machine, comprising in combination a machine frame, a flyer journalled in said frame and consisting of four discs connected by rods, a winding frame locked in position of rest within said flyer, a closing die on the outer side of said machine frame on the feed end of the machine and adapted to lay the rope prior to its entrance into the machine, a guide pulley on the second disc from the feed end of the machine adapted to guide the rope laid by said closing die, a reversing pulley carried by the third and fourth flyer discs and 30 adapted to change the direction of travel of the rope and feed the same to said winding frame, and means for guiding the rope over said reversing pulley obliquely to the plane of rotation of 35 said pulley, said pulley having a face domed from the middle towards both sides to cause the rope to roll thereon in the direction of rotation of the flyer when running obliquely over the pulley.

4. A high speed rope making machine, comprising in combination a machine frame, a flyer journalled in said frame and consisting of four discs connected by rods, a winding frame locked in position of rest within said flyer, a closing die on the outer side of said machine frame on the feed end of the machine and adapted to lay the rope prior to its entrance into the machine, a guide pulley on the second disc from the feed end of the machine adapted to guide the rope laid by said closing die, a reversing pulley carried by the third and fourth flyer discs and 40 adapted to change the direction of travel of the rope and feed the same to said winding frame, and means for guiding the rope over said reversing pulley obliquely to the plane of rotation of 45 said pulley, said pulley having a face formed by recessed bulged portions of similar width extending from the middle and the side edges of 50 the pulley.
